NO. 14,563

JAN 22, 1884

UNITED STATES PATENT OFFICE.

LEVI K. SMEDES, OF MOUNT VERNON, ASSIGNOR TO TAYLOR & CO., OF NEW YORK, N. Y.

DESIGN FOR A BURIAL-CASKET.

SPECIFICATION forming part of Design No. 14,563, dated January 22, 1884.

Application filed November 8, 1883. Term of patent 7 years.

To all whom it may concern:

Be it known that I, LEVI K. SMEDES, a citizen of the United States, residing at Mount Vernon, in the county of Westchester and State of New York, have invented and produced a new and original Design for Burial-Caskets, of which the following is a specification.

The principal feature of my design consists of intermediate columns combined with end columns, substantially as illustrated in the accompanying photograph, which shows a portion of a casket containing my design. In this photograph the letter A designates the body of the casket; B an intermediate column, and C an end column, thereof. These columns B C are similar in style to each other, each being formed with a square base, B' or C', a square capital, B² or C², and a circular top, B³ or C³, surmounting the capital. The top or

"frame" D of the casket intersects the capital B² C² of the columns, and is ornamented with moldings E F, one of ogee shape and the other of cavetto shape. By these features I obtain a casket of novel and characteristic appearance.

What I claim as new, and desire to secure by Letters Patent, is—

In the design for a burial-casket having intermediate and end columns, the square capitals to the columns and the frame intersecting the capitals, as shown and described.

In testimony whereof I have hereunto set my hand and seal in the presence of two subscribing witnesses.

LEVI K. SMEDES. [L. S.]
